SPECTACLE FRAME OR THE LIKE

Joseph J. Margules, Southbridge, Mass., assignor to American Optical Company, Southbridge, Mass., a voluntary association of Massachusetts

Application October 31, 1955, Serial No. 38,668

Term of patent 14 years

(Cl. D57—1)

Fig. 1

Fig. 1 is a front elevational view of a spectacle frame embodying my new design; and

Fig. 2 is a top plan view thereof, with the ends of the temples broken off for convenience of illustration.

The characteristic features of my design are shown in full lines in the drawing.

I claim:

The ornamental design for a spectacle frame or the like, substantially as shown and described.
